UNITED STATES PATENT OFFICE.

JAMES E. JOURNEAUX AND WILLIAM E. HEBESTREIT, OF DETROIT, MICHIGAN.

DESIGN FOR A SIGNAL-EXHIBITOR CASING.

58,238.

Specification for Design. Patented June 28, 1921.

Application filed January 17, 1921. Serial No. 438,012. Term of patent 3½ years.

To all whom it may concern:

Be it known that we, JAMES E. JOURNEAUX and WILLIAM E. HEBESTREIT, citizens of the United States, residing at Detroit, in the county of Wayne, State of Michigan, have invented a new, original, and ornamental Design for a Signal-Exhibitor Casing, of which the following is a specification, reference being had to the accompanying drawing, forming part thereof.

Figure 1 is a front elevation of a signal exhibitor casing;

Fig. 2 is a side view of the same, and Fig. 3 is a plan view, showing our new design.

We claim:

The ornamental design for a signal exhibitor casing, as shown.

JAMES E. JOURNEAUX.
WILLIAM E. HEBESTREIT.
